SHOE INNERSOLE

Filed April 4, 1941

UNITED STATES PATENT OFFICE

2,336,155

SHOE INNERSOLE

Fred L. Ayers, Watertown, Mass.

Application April 4, 1941, Serial No. 386,914

2 Claims. (Cl. 36—22)

This invention relates to shoe innersoles, more particularly of the type wherein a layer of canvas is secured to the lower face of a thin top layer or sole blank, the outer margins of the canvas being unsecured so that inseam fasteners can be passed through the canvas layer inwardly of the periphery of the top layer or blank. In order to define the outer limit of the secured portion of this layer, the parts may be stitched together or otherwise secured through and through by fastenings at the desired distance inwardly of their margins. While this method is satisfactory in so far as defining a free margin of the reinforcing fabric for receiving the inseam fastenings is concerned, it has the disadvantage that the stitches or other fastenings by which the canvas is secured to the upper layer or blank are exposed on the top face of the innersole, and to avoid this in the finished shoe the innersole is overlaid with a sock lining which is inserted in the shoe after the shoe has been made, this being a troublesome and somewhat expensive operation.

The present invention has for an object, therefore, to provide an innersole presenting a fabric portion around the margin of its lower face either around the forepart, the forepart and shank or entirely around the innersole, depending upon how it is desired to finish the heel and shank portions of the shoe, this fabric portion being secured inwardly of the margin of the body of the innersole but without the use of stitching or other fastenings showing on the upper face of the innersole.

The invention may be carried out in accordance with one method by avoiding the use of stitches or other fastening elements and making use of other means for defining the inner limit of the unsecured margin of the fabric.

In accordance with other methods, stitching or other fastening elements may be employed, but in such a manner that such stitching or elements are covered over and concealed by another or other portions of the innersole.

For a more complete understanding of this invention, reference may be had to the accompanying drawing in which

Figure 1 is a perspective view partly broken away showing one form of innersole embodying the invention.

Figure 2 is a detail section of two elements of the same partly separated to more clearly show the construction.

Figure 3 is a detail section to a larger scale than Figure 1 through one side portion of the

innersole but with the marginal lip turned downwardly.

Figure 4 is a view similar to a portion of Figure 3 but showing a modification.

5 Figure 5 is a view similar to Figure 4, but showing the margin turned as in Figure 3.

Figures 6 and 7 are views similar to Figures 3 and 5, but showing further modifications.

10 Figure 8 is a plan view of an innersole layer which may be used in the construction of Figures 1 to 3, inclusive, and 5 and 7 if desired.

Figure 9 is a cross section through an innersole member preparatory to securing the fabric reinforcement thereto.

15 Figure 10 is a similar view but showing the innersole member and the fabric reinforcing member adjacent to each other and prepared for securing together.

Figure 11 is a lateral section through the completed innersole employing the parts shown in Figure 10.

Figures 12, 13 and 14 are fragmentary views similar to Figures 4 and 6 but illustrating further modifications.

25 Referring first to the construction shown in Figures 1, 2 and 3, at 1 is indicated a sole blank which may be of relatively thin material and unprovided with any marginal lips or ribs. To the lower face of this blank 1 is secured a fabric

30 reinforce comprising superposed fabric layers 2 and 3. The fabric layer 3, at least around the forepart of the innersole, is extended outwardly beyond the margin of the blank, but it may also be so extended at the shank or even

35 around the heel as well if desired, this depending upon the manner of lasting which it is desired to use in the shank or heel or both. These layers 2 and 3 are secured together somewhat inwardly of the margin of the layer 2, which is the same size as the blank 1, by a line of fastenings such as stitching 4.

40 Preferably the upper layer 2 is provided with a cement coating 5 on its upper face, this being if desired of the same nature as that on the usual canvas reinforcement for "Gem" innersoles.

45 The lower layer 3 may be of the same material, but preferably its cement coated face is downwardly presented as shown at 6. The two fabric layers thus secured together are cemented by the cement layer 5 to the lower face of the blank 1. This provides a construction wherein no stitching or other fastenings appear on the top face of the innersole so that after insertion in a shoe no sock lining need be placed in position. The placing of such a sock lining,

when used, is after the shoe has been made and it is a troublesome matter for the workman to insert such a sock lining and secure it properly lined up with the innersole. Furthermore, the insertion of this sock lining through the open top of the shoe results in more or less distortion of the shoe upper thus impairing its appearance unless it be subjected to later finishing operations.

The line of stitching 4 as shown in Figure 1 is positioned inwardly of the outer margin of the blank 1 so that the outer margin 7 of the fabric layer 3 is free to be turned downwardly about the stitching and serve as a rib to receive inseam stitching (not shown), after which this portion 7 may be folded inwardly with its adhesive coated face in contact with the adhesive coated lower face of the layer 3 inwardly of the fastenings 4 as shown in dotted lines in Figure 3. This provides a very secure anchorage for the inseam stitches and yet produces an innersole face substantially flat from side to side, since when the portion 7 is pressed against the lower face of the fabric layer inwardly of the line of fastenings 4, it presents no substantial thickness. It does, however, leave exposed a face of fabric uncoated by the cement and in condition to receive a permanent cement such as well known pyroxylin cement by which an outersole may be secured directly thereto. Such an arrangement is not claimed herein, but forms subject matter of a co-pending application.

In place of employing a lower layer extending entirely across the width of the innersole, a marginal fabric portion 10, as shown in Figures 4 and 5, may be employed. This may be secured to an upper reinforcing fabric layer 2a as by one or more lines of stitching as at 11. When the margin 12 of this layer 10 is turned downwardly about the outermost line of stitching 11, it may act as an inseam stitch-receiving rib just as the margin 7 of Figure 3 is used and after the stitching is laid, this margin 12, which is preferably wider than the portion 14 secured to the layer 2a, may be brought down into contact therewith overlying the stitching or other fasteners 11 and the inner edge of the part 14 as shown in dotted lines in Figure 5.

In Figure 6 a further modification is shown in which the blank 1a is slit inwardly around its margin, at least around the forepart, and if desired through the shank portion or both the shank and heel, as shown at 15, thus to form upper and lower lips 16 and 17. A fabric reinforcing layer 18, preferably with its cement coated face downwardly turned, is secured to the lip 17 only, as by the line of stitching or other fasteners at 19, so that its portion outwardly of the fasteners 19 may be bent downwardly to form a stitching rib and thereafter folded inwardly as has been previously described with reference to the portions 7 and 12 shown in Figures 3 and 5. In order to get at the parts for inserting the stitches or fasteners 19, the upper lip 16 may be temporarily turned up as shown in dotted lines in Figure 6.

In Figure 7 a further modification is shown in which the insole blank comprises a pair of fabric layers 20 and 21. The layer 21 only, is secured to the bottom reinforcing fabric layer 22 as by the line of stitches or other fasteners at 23, and the upper layer 20 has its margin which extends beyond the margin of the layer 21 folded around the margin of the layer 21 and secured as by

5 cement to the lower face of this layer outwardly of the margin 24 of the bottom layer 22 which has been turned downwardly outwardly of the line of fasteners 23 to form the stitching lip. This stitching lip may be folded back into the dotted line position and secured to the lower face of the innersole after the stitches or other fasteners have been placed.

In all the constructions heretofore described, it will be noted that the fabric reinforcing layer, the margin of which forms the inseam receiving lip, is secured to the remainder of the innersole by fastenings such as stitches, but that in no instance do these fastenings or stitches extend through the top face of the innersole where they will be visible in the completed shoe should no sock lining be applied to the top face of the innersole.

Where a double fabric layer is employed, as shown in Figures 1, 2, 3, 5 and 7, the inner of these layers may be cut out as shown at 25 in Figure 8 so as to present merely a marginal portion 26. This tends to make the construction more flexible. A continuous layer will usually be found preferable where only one layer is used.

In Figures 9, 10 and 11 a further modification is shown in which no fastenings are used to secure the reinforcing fabric layer to the remainder of the inner sole. The bond between this fabric layer and the remainder of the innersole is by cement only, but means are provided to insure a clean line of demarcation where the adhesive which secures these parts together terminates so that the outer margin of the reinforcing layer may be turned away from the remainder of the innersole to form a stitch-receiving rib as in the constructions heretofore described. To this end the blank 1b, which may be of leather or other suitable material, is first coated around its margin on its lower face where the reinforcing layer is to extend with a cement insulator composition as at 30. By "cement insulator" is meant some material with which the cement will not bond or at least will not strongly bond. There are many well known materials for this purpose such as compositions containing oil or wax or wax alone. This coating 30 is applied in a relatively narrow band having a clean cut inner edge so as to define a zone around the margin of the blank where cement will not adhere. The lower face of this blank is then coated with the adhesive as shown at 31 in Figure 10, the margins being thus free from the cement and the fabric reinforcement is secured to the blank 1b by means of this cement. If a fabric cement coated on one face is to be employed, the uncemented face of the fabric coating is, preferably, arranged to face the blank 1b. The parts are then brought together as shown in Figure 11 and the cement bond between the reinforcing fabric and the blank is allowed to set or harden. That portion of the margin of the reinforcing layer 32 which contacts with the insulator coating 30 is then left free so that it can be brought downwardly as shown at 33 in Figure 11 to form the inseam receiving rib and may thereafter be turned inwardly and cemented to the lower face of the layer 32 inwardly of the inseam fasteners.

In Figures 12, 13 and 14 other constructions are illustrated in which no stitches or other fasteners are used to secure the fabric reinforcement to the sole blank. In these constructions the lower margin of the blank 40, at least about 70 the forepart, is cut away as by a marginal rab-

bet to form an abrupt marginal outwardly facing shoulder spaced inwardly from its periphery as shown at 41, defining the outward marginal limit of the cement securing of the reinforcing layer 42 which when flat, projects outwardly of the shoulder 41. The cut face of the blank outwardly of the shoulder 41 may be parallel to the adjacent face of the blank as shown in Figure 12, or upwardly or downwardly inclined as shown in Figure 13 or 14, respectively, and may be coated with a cement insulator, if desired. Due to the thinness of the margin, however, it will usually be found desirable to treat it with some stiffening agent. Such agents are well known in the art and commonly contain shellac or other gums or resins. Such a shoulder 41 could also be employed in connection with other means than cement for securing the reinforcing fabric to the sole blank.

From the foregoing description of certain embodiments of this invention, it will be noted that in each of these the reinforcing fabric is uncured about the margin of the remainder of the innersole so that the inseam stitching or other fastening may be positioned inwardly of the innersole margin, but in no case is there any fastening means between the reinforcing fabric layer and the remainder of the innersole visible

on the top face of the innersole. Thus there is no occasion for employing a sock lining in the completed shoe.

It will be also understood that various other changes and modifications might be made without departing from the spirit or scope of this invention.

I claim:

- 10 1. An innersole including a blank provided with a marginal rabbet on one side face forming an outwardly presented abrupt shoulder extending back from said one side face, and a reinforcing layer secured to said face entirely by cement and only as far outwardly as said shoulder and when in flat condition projecting outwardly of said shoulder.
- 20 2. An innersole including a blank provided with a marginal rabbet on one side face forming an outwardly presented abrupt shoulder extending back from said one side face, and a reinforcing layer secured to said face entirely by cement and only as far outwardly as said shoulder and when in flat condition projecting outwardly of said shoulder, the base face of said rabbet being inclined downwardly and outwardly to the face of the blank inwardly of said shoulder.

FRED L. AYERS.
